(57) **CLAIM**

The ornamental design for a water bottle with closure, as shown and described.

DESCRIPTION

FIG. 1 is a front, top perspective view of a water bottle with closure;

FIG. 2 is a rear, top perspective view thereof;

FIG. 3 is a front, top perspective view thereof, shown with the ring in a raised configuration;

FIG. 4 is a rear, top perspective view thereof;

FIG. 5 is a front elevation view thereof with the ring in a lowered configuration;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a front elevation view thereof with the ring in a raised configuration;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, top perspective view of a closure, shown separately for clarity of disclosure;

FIG. 18 is a rear, top perspective view thereof;

FIG. 19 is a front, top perspective view thereof, shown with the ring in a raised configuration;

FIG. 20 is a rear, top perspective view thereof;

FIG. 21 is a front elevation view thereof with the ring in a lowered configuration;

FIG. 22 is a rear elevation view thereof;

FIG. 23 is a left side elevation view thereof;

FIG. 24 is a right side elevation view thereof;

FIG. 25 is a top plan view thereof;

FIG. 26 is a bottom plan view thereof;

(Continued)

FIG. 27 is a front elevation view thereof, shown with the ring in a raised configuration;

FIG. 28 is a rear elevation view thereof;

FIG. 29 is a left side elevation view thereof;

FIG. 30 is a right side elevation view thereof;

FIG. 31 is a top plan view thereof; and,

FIG. 32 is a bottom plan view thereof.

The portions of the water bottle with closure shown in broken lines form no part of the claimed design.

1 Claim, 32 Drawing Sheets
